JOHN BOND TREVOR, OF YONKERS, NEW YORK.

BOTTLE-CLOSURE.

1,179,147.

Specification of Letters Patent. Patented Apr. 11, 1916.

Application filed October 14, 1915. Serial No. 55,809.

To all whom it may concern:

Be it known that I, JOHN B. TREVOR, a citizen of the United States, and a resident of Yonkers, in the county of Westchester, and State of New York, have invented a new and Improved Bottle-Closure, of which the following is a full, clear, and exact description.

This invention relates to closures and particularly to a bottle closure, and has for an object to provide an improved construction which will positively seal the bottle.

Another object in view is to provide a closure formed with sealing material arranged thereon of a pliable nature so as to positively seal a bottle or other receptacle to which it is attached, even though the same may be irregular or rough.

A still further object in view is to provide a closure formed on the order of a cup with corrugations and with a covering of filling material, such as paraffin, whereby the closure is adapted to close bottles, jars and the like having openings differing slightly in sizes.

In the accompanying drawings: Figure 1 is a top plan view of a closure embodying the invention; Fig. 2 is a section through Fig. 1 on line 2-2; Fig. 3 is a sectional view through a closure and the neck of a bottle together with a stopper, the same disclosing an embodiment of the invention applied; Fig. 4 discloses a removable stopper used in connection with the closure shown in Fig. 1; Fig. 5 is a view similar to Fig. 4 but showing the cup disclosed in Fig. 4 applied thereto; Fig. 6 is a further slightly modified arrangement disclosing the cup pressed or crimped over the bead of the neck of the bottle.

Referring to the accompanying drawings by numerals, 1 indicates the cup in its entirety, which is provided with a corrugated wall 2 and a bottom 3, preferably flat. The corrugations in wall 2 are filled with a suitable form of plastic material, as for instance paraffin 4. The paraffin 4 covers the entire outer wall, there being a greater supply in the corrugations than on the wall. This paraffin may be applied in any suitable manner, as for instance by dipping while the paraffin is in a liquid state. After the cup or cover 1 has been prepared in the manner just described, the same is inserted into the neck of the bottle, as for instance the neck 5 shown in Fig. 3. The stopper 6 is then

applied, which may be of cork or of other material as preferred. When the cork stopper 6 has been forced into position the corrugations on the wall 2 will become somewhat straightened, if not entirely straightened out and the wax or paraffin, in case paraffin is used, is forced against the neck 5 and thereby caused to fill all the small indentations or rough places in the neck, thus producing a positively airtight closure.

Instead of using the cork stopper 6 a stopper 7 of metal or other suitable material is provided, as shown in Fig. 4, which is preferably formed with a plurality of ears 8 adapted to be bent over a bead 9, as shown in Fig. 5, when the stopper is in this position. The action of this stopper is the same as that of stopper 6 except for the use of the ears 8 which not only hold the stopper in place but present means by which the stopper may be readily removed at any time.

In Fig. 6 a slightly modified arrangement is presented to that shown in Figs. 1 and 2, wherein the cup 1 is provided with an overhanging flange 10 pressed or crimped around the bead 9 for limiting the downward movement of the cup. The side wall 2 is made similar to side wall 2 of the preferred structure and any desired form of stopper may be applied for squeezing the cup and paraffin covering against the neck 5 of the bottle.

It will be noted that in all forms of the invention a substantially cup-shaped closure is presented which either is dipped entirely in paraffin or some other similar material or the outside is covered with such material so that when pressed tightly into position the bottle will be hermetically sealed by reason of the fact that the paraffin will enter small indentations or rough places of the bottle. The arrangement is such that the corrugations allow a free expansion of the closure so as to adapt the same to variations and irregularities in the sizes of bottle necks. The corrugations also present means for carrying a supplementary or extra charge of paraffin, or if desired, of an adhesive for producing a proper tight connection between the parts.

What I claim is:—

1. A closure for bottles and the like, comprising a cup-shaped member having corrugated walls, a paraffin covering for said walls, said corrugations carrying an extra

thick layer of paraffin, and a resilient stopper engaging the interior of the cup-shaped member for pressing said walls of said cup-shaped member, so that the paraffin in said corrugations will produce an air-tight connection.

2. A closure for bottles and the like, comprising a cup-shaped member having corrugated walls, a paraffin covering for the walls, said corrugations carrying an extra supply of paraffin, and a cup-shaped stopper formed with overhanging ears, said

stopper pressing the walls of said cup-shaped member and said overhanging ears limiting the movement of the cup-shaped 15 stopper when the same is being applied.

In testimony whereof I have signed my name to this specification in the presence of two subscribing witnesses.

JOHN BOND TREVOR.
